United States Patent Office.

WILLIAM DOYLE, OF BIRMINGHAM, PENNSYLVANIA.

Design No. 4,260, dated July 26, 1870.

DESIGN FOR A JELLY-GLASS.

The Schedule referred to in these Letters Patent and making part of the same.

To all whom it may concern:

Be it known that I, WILLIAM DOYLE, of the borough of Birmingham, county of Allegheny, State of Pennsylvania, have originated and designed a new Pattern for Jelly-Glasses, of which the following is a full, clear, and exact description, reference being had to the accompanying drawings making part of the specification.

The object of this invention is to produce a jelly-glass, having a ring formed of glass around the jelly-glass, at a suitable distance from the top. This plain part, from the said ring to the top of the jelly-glass, to be made straight, so that a metallic cover, having a suitable flange to correspond with the plain on the jelly-glass, will fit nicely without the use of rubber bands or other flexible material; also without the use of any cement, as the metallic cover, being made thin, will be sufficiently elastic to fit closely to the jelly-glass. The edge of the flange of the metallic cover to rest on the ring formed on the jelly-glass, and, when the metallic cover is placed on the jelly-glass, will form a much better jelly-glass than has ever before been

used for the purpose, and, besides, make a very handsome article.

Figure 1 is a jelly-glass, shown without a metallic cover, having a glass ring formed around it near the top.

Figure 2 is a jelly-glass, showing the jelly-glass complete, with metallic cover attached.

Figure 3 is the metallic cover.

Fig. 1, letter *b*, represents the plain straight part to fit the flange *a*, fig. 3.

c, in fig. 1, represents the glass ring formed around the jelly-glass to hold the metallic cover firmly in place.

Having fully described my invention, What I claim, and desire to secure by Letters Patent, is—

The design for jelly-glasses, as shown and described. WILLIAM DOYLE.
